UNITED STATES PATENT OFFICE.

JOSEPH K. FISHER, OF SANTA MONICA, CALIFORNIA, ASSIGNOR TO J. EDWARD OGDEN,
OF MOUNTAINVILLE, NEW YORK.

EXPANSION SHIELD.

Application filed February 6, 1922. Serial No. 534,293.

This invention relates to expansion shields and particularly to sheet metal shields.

One of the objects of the invention is to provide a device of the character described which will effectively secure or hold a bolt or screw in material such as wood, stone, brick or cementitious material with which the threaded element cannot directly obtain a secure hold.

Another object of the invention is to provide a simple construction of expansion shield that may be economically manufactured.

Another object of the invention is to provide an expansion shield having means for effectively engaging the wall of an opening in which the shield is placed, this means also serving to resist the withdrawal of the shield and to retain it securely in place.

Further objects of the invention will appear from the following description taken in connection with the drawings which form a part of this application and in which

Fig. 1 is an elevation, partly in section, of an expansion shield constructed in accordance with the invention.

Fig. 2 is an elevational view taken at right angles to Fig. 1.

Fig. 3 is an end elevation of the inner end of the shield shown in Fig. 1.

Fig. 4 is an end elevation of the other end of the shield shown in Fig. 1.

Fig. 5 is a plan view of the blank from which the sections of the shield shown in Figs. 1-4 may be made.

Figs. 6 and 6^A are elevations of modified forms of stiffening ribs.

Fig. 7 is an end elevation of the inner end of another form of shield constructed in accordance with the invention.

Fig. 8 is an end elevation of the opposite end of the shield shown in Fig. 7.

Fig. 9 is a plan view of a blank from which the shield shown in Figs. 7 and 8 may be constructed.

Fig. 10 is an end elevation of the inner end of another form of shield constructed in accordance with the invention.

Fig. 11 is an end elevation of the opposite end of the shield shown in Fig. 10.

Fig. 12 is a plan view of the blank from which the shield shown in Figs. 10 and 11 may be formed.

Figs. 13 and 14 are respectively a plan view of a blank and an end elevation of the

inner end of a shield formed therefrom and constructed in accordance with the invention.

Fig. 15 is an elevation of a portion of the shield shown in Figs. 13 and 14 and showing the corrugated ribs.

Fig. 16 is a view similar to Fig. 15 but showing another form of the corrugated ribs.

Fig. 17 is a view similar to Figs. 15 and 16 but showing another form of corrugations or bends in the ribs.

Fig. 18 is an end elevation of the inner end of another form of shield constructed in accordance with the invention.

Fig. 19 is a sectional elevation of a part of the shield shown in Fig. 18 and taken substantially in line 19-19 of Fig. 18.

Figs. 20, 21 and 22 are respectively a side elevation and end elevations of the two ends of another form of shield constructed in accordance with the invention.

Fig. 23 is a plan view of a blank from which the shield shown in Figs. 20-22 may be formed.

Fig. 24 is a plan view of a blank from which another form of expansion shield embodying the invention may be formed.

Fig. 25 is an elevation of a portion of still another expansion shield constructed in accordance with the invention.

Fig. 26 is a plan view of a portion of a blank from which the shield shown in Fig. 25 may be made.

The invention by means of which the foregoing objects are attained consists briefly of a sheet metal expansion shield comprising a tubular member having expansible elements and having transversely corrugated or bent, longitudinally extending projections or ribs. In certain of the embodiments of the invention shown in the drawings, the tubular member has a tapered bore and ribs are provided on the outer tapered portion of the shield and increase in width as the section of the bore decreases. These ribs are transversely bent or corrugated. In another embodiment the ribs extend inwardly instead of outwardly.

Like characters of reference designate corresponding parts throughout the several views of the drawings.

In Figs. 1-5 inclusive an expansion shield is illustrated comprising a pair of expansible elements 20 and 21 secured together by a split ring 22 or any other suitable securing

means. The expandible elements or members 20 and 21 are transversely folded or bent to form a tapered bore, having an elongated section as shown in Fig. 3 at the inner 5 end, resembling an ellipse, and having a cylindrical section as shown in Fig. 4 at the outer end.

The edges of the two sections or elements 20 and 21 are bent outwardly as shown at 23 10 to form longitudinal ribs or flanges 24. These ribs are corrugated, preferably throughout their length, and, in the embodiment shown in Figs. 1-5, the corrugations in the adjacent or abutting ribs interfit as 15 clearly shown in Fig. 1. It will also be noted that the ribs or flanges 24 increase in width or depth as the section of the tapered bore decreases and as shown in Fig. 3 the outer edges of the ribs lie substantially in 20 the same cylinder as the cylindrical outer surface of the outer end 25 of the shield.

The ribs 24 in the adjacent flanges by reason of their interfitting assist in retaining the sections 20 and 21 against relative 25 longitudinal displacement and the corrugations also materially strengthen or stiffen the longitudinal ribs.

In Figs. 6 and 6^A other forms of bends or corrugations are shown and these forms may be used in the shield shown in Figs. 1-5 or in the forms hereinafter described.

In Figs. 7-9 inclusive another embodiment of the invention is illustrated and the shield shown in Figs. 7 and 8 may be formed 35 from a blank such as that shown in Fig. 9. This blank has its side edges 30 and 31 slightly flared and the edge 31 is provided with teeth or serrations 32 at one end thereof. The teeth 32 are adapted to fit in corresponding notches 33 formed in the corresponding end of the edge 31 when the blank is folded transversely into a tube. The blank is also folded upon fold lines 34 and 35 to form longitudinal, folded ribs 36 and 40 37. The edges 30 and 31 are also bent outwardly to form longitudinal flanges or ribs 38 corresponding to the ribs 24 in the embodiment shown in Figs. 1, 2 and 4. The longitudinal, folded ribs 36 and 37 and the 45 ribs 38 are transversely corrugated in a manner similar to the ribs 24.

In Figs. 10, 11 and 12 another form of the invention is shown and in this form the blank 40 has a plurality of longitudinally extending, integrally connected sections 41. The blank 40 is folded transversely into a tube and the longitudinal edges of the sections 41 are bent outwardly as shown at 42 forming ribs or flanges 43. The bore of the 50 tube is tapered or restricted as in the other forms of the invention and the flanges or ribs 43 abut and are transversely corrugated in such a manner that the corrugations of the adjacent ribs interfit.

65 In Figs. 13 and 14 are shown another form

of blank and shield formed therefrom. In this embodiment the blank 45 has a plurality of longitudinal sections 46 and the blank is folded transversely into the shield shown in Fig. 14. In folding the blank the edges of 70 the sections 46 are turned outwardly forming flanges or ribs 47 which are bent or corrugated in some such form as shown in Figs. 15, 16 and 17. As shown in these figures the corrugations or bends may register as in 75 Fig. 15 or may come opposite each other as in Figs. 16 and 17.

It should also be noted that the adjacent ribs or flanges in Fig. 10 are in contact with each other, whereas in Fig. 14 the ribs are so spaced.

In Figs. 18 and 19 is shown another form of shield embodying the invention. In this form the ribs 48 are formed by bending the edges of the shield inwardly instead of outwardly as in the preceding forms. The ribs are bent transversely or corrugated as shown in the other embodiments.

In Figs. 20-23 inclusive, another form of the invention is illustrated and in this embodiment the shield is formed from the blank shown in Fig. 23. This blank comprises a pair of oppositely extending sections 50 and 51 separated substantially throughout their width by a slit 52, the sections being 90 connected by tabs 53 disposed substantially in alinement with the slit and beyond the ends thereof. This blank is folded transversely on an axis substantially coinciding with the slit 52 and the sections are separated to form a tubular member. The tabs 53 are then folded back against the outer surface of the member as shown in Figs. 20 and 21. The sections 50 and 51 are bent inwardly to form a tapered bore and the edges 95 of the sections are bent outwardly as shown in Fig. 22 and are transversely corrugated forming longitudinally extending ribs similar to those shown in the preceding figures.

Another form of blank from which an expansion shield constructed in accordance with the invention may be made is shown in Fig. 24. In this instance the sections 60 and 61 will be folded about the central section 62 and will be folded transversely into a tubular member. In this folding process the bore of the tubular member will be tapered and the edges of the sections will be bent outwardly to form longitudinal ribs and the ribs will be transversely corrugated in the 110 manner already described.

In Figs. 25 and 26 still another form of the invention is shown. In this embodiment a blank such as that shown in Fig. 26 may be used and the tubular member is formed by 125 folding the sections or arms 70 and 71 about the central section and drawing the metal to form a cupped end 72. The sections are also folded in a manner to form a tapered bore and the edges of the sections are bent out- 130

wardly to form the longitudinal ribs which are transversely corrugated.

From the foregoing specification it will be seen that a simple, practical and effective form of expansion shield has been designed and it will be understood that the longitudinally extending, transversely corrugated or bent ribs or projections will effectively stiffen the shield and will securely retain the shield in position in the opening in which it is placed.

Although regularly disposed corrugations are shown in some figures of the drawings, it is obvious that the longitudinal ribs may be stiffened by lateral bends of any desired shape. Moreover the word "corrugated" is used in the claims in its broadest sense and is intended to cover any form of lateral bends.

Although certain specific embodiments of the invention have been illustrated and described it will be understood that the invention is capable of further modification and that further changes in the construction and in the arrangement of the various cooperating parts may be made without departing from the spirit or scope of the invention as expressed in the following claims.

What I claim is:

1. A sheet metal expansion shield comprising a plurality of expansible sections having out-turned edges forming longitudinal ribs, the ribs formed by adjacent edges having transverse, interfitting corrugations.

2. An expansion shield having walls of a single thickness and comprising a pair of expansible elements, each element having its longitudinal edges bent outwardly to form longitudinal ribs, the ribs being corrugated

transversely, the corrugations on adjacent ribs being interfitting.

3: An expansion shield having a tapered bore and having longitudinally extending transversely corrugated ribs on its outer surface, increasing in width as the bore decreases in section.

4. An expansion shield having a tapered bore and having longitudinally extending, abutting, transversely corrugated ribs on its outer surface, increasing in width as the bore decreases in section.

5. A sheet metal expansion shield comprising a plurality of expansible members forming a tapered opening decreasing in size toward the inner end of the shield, each of said members having a longitudinal, outwardly extending, transversely corrugated rib of folded metal.

6. A sheet metal expansion shield comprising a tubular member having a tapered bore and longitudinally extending, transversely corrugated, folded, flanges increasing in height toward the smaller part of the tube.

7. An expansion shield comprising a tubular sheet metal member having a plurality of arms constructed to form a tapered bore, the adjacent edges of the arms being bent outwardly, transversely corrugated, and tapered oppositely to the taper of the bore.

8. A sheet metal expansion shield comprising a plurality of expansible members forming a tapered opening decreasing in size toward the inner end of the shield, each of said members having a longitudinal, transversely corrugated rib of folded metal.

In witness whereof, I have hereunto set my hand this 30th day of January, 1922.

JOSEPH K. FISHER.
